United States Patent

Des. 241,538
Patented Sept. 21, 1976

241,538

ELECTRONIC FLASH UNIT

Samuel F. Swayze, Rochester, N.Y., assignor to Eastman
Kodak Company, Rochester, N.Y.

Filed Apr. 8, 1975, Ser. No. 566,637

Term of patent 14 years

Int. Cl. D16—05

U.S. Cl. D16—42

FIG. 1

FIG. 4

FIG. 2

FIG. 3

FIG. 5

FIG. 6

FIG. 7

FIG. 1 is a front perspective view of an electronic flash unit showing my new design;

FIG. 2 is a front elevational view thereof;

FIG. 3 is a right side elevational view thereof;

FIG. 4 is a left side elevational view thereof;

FIG. 5 is a top plan view thereof;

FIG. 6 is a bottom plan view thereof; and

FIG. 7 is a rear elevational view thereof.

I claim:

The ornamental design for an electronic flash unit, as shown.
